(54) **WATER PROOF LEATHER & CLOTH**

(76) Inventor: **J.L. Comstock**

S. J. Comstock.
Seth Comstock

The Schedule referred to in these ~~Letters~~^{Patent} and making part of the same, containing a description in the words of the said J. S. Comstock himself of his discovery, being a method of making water proof cloth, leather, & cloaks, shoes, hose, carriage tops, carriage seats, & carriages, life preservers, boats, sheet balloons, gas tubes, mail & travelling bags and for other purposes whereof the subscriber claims for himself the discovery.

It has long been a desideratum in the art and manufacture of life boats to have some cheap substance which being applied to cloth and leather would render them impervious to water, without destroying their flexibility or other good qualities. For this purpose India Rubber or Gum elastic has been subjected to a great variety of experiments as the substance by means of which such an object was most likely to be attained. But the difficulty has hitherto been to find a cheap solution which after reducing the gum to a solution which it could be applied with a brush would again coagulate and leave it in its original dry, impervious and elastic state.

It is sometimes often especially when washed that long been a known solvent of this gum but the difficulty of spreading the solution owing to the sudden evaporation of the ether together with its high price will always forbid its employment for common purposes.

It is also the oil distilled from tar obtained by roasting of bituminous coal, is also a solvent of India Rubber but this solution is entirely unfit to be employed on articles for personal use on account of the very unpleasant smell which it emits and which it retains even for years.

The松脂油 and the 蜜蜡 which may be distilled from the Barbados tar through of them solvents are equally objectionable on the same account.

Spirit of turpentine it is well known to chemists, and perhaps to others, is a solvent of gum elastic, and many experiments have been made to bring this solution to a state in which it might be employed exclusively for useful purposes, but it is believed that hitherto no valuable use has been made of this composition. The subscriber has however discovered that this composition, viz. Gum elastic dissolved in spirit of turpentine, may be employed for many valuable purposes when applied according to the following specifications.

Specification 1. Take a sheet or sole of leather and if it is blacked on the flesh side shave off with a curving knife the surface of the leather or grain side so that the water proof paste may adhere the stronger. If the sole is blacked on the smooth or grain side the shaving is unnecessary. Next let the skin be whitened, and extended with snuff or otherwise, on a smooth flat surface, and when it is dry spread with a brush on the undressed side of the leather a solution of gum elastic in spirit of turpentine. When one coat is dry, spread another, in a proportion a third when the surface will be completely covered with a skinning coat of gum elastic. Then extend a piece of leather or other elastic in hair with leather hooks, and on one side lay two or three coats of the solution waiting as before for each coat to dry before another is applied. Lastly when the two coated surfaces are nearly dry bring them into close contact by passing them over each other, coat to coat, between a pair of wooden or iron rollers. This leather is employed in the manufacture of bags and other purposes.

Specifying the leather for gentlemen's boots only the feet are made water proof.

Spec. 2d. To make water proof boots let the fronts be blacked over and out in the usual manner, then let the part which forms the foot be unfilled or shaved on the inside, as directed above. Then cut the lining of buckskin or other leather of the edges of the foot of

the knot, letting it come up to the angle. Next spread the solution on the side which has been shaved, and do the same to the rough side of the lining; and when nearly dry, unite these two surfaces by passing them through the stitching, ^{piece}, in the making, let the stitches of the mitten be covered with the solution and let these be inserted between the inner and outer soles a lining of water proof leather laying the outer side next the sole.

Spec. 3. To make water proof cloth, extend the solution on both sides and apply the solution as above described to one side of each piece until the surface of each presents a shining appearance and the threads are accurately covered, then bring the two coated surfaces into close union by passing the cloth between a pair of rollers.

Spec. 4. To make water proof shoes of Brocchia, proceed as in Spec 1 and apply from side or as a lining for the Brocchia, thin cotton or linen cloth, and in making, cover the stitches of the mitten, and unit a water proof lining of leather as directed for the boots Spec 5. In the making of water proof clothing, cut out, and sew the garment together as usual, then protect the same by stitching strips of water proof cloth over them on the inside.

By following these directions boots & shoes of leather or cloth and clothing of all kinds may be rendered entirely impervious to water, the article still retaining an equal degree of pliability. It is found also by experience that boots and shoes of this kind, are much more durable than those made in the ordinary manner.

I claim as my discovery; the application of gum elastic dissolved in spirits of turpentine for the purpose of rendering water proof leather and water proof cloth, as described in the foregoing specification.
